TYPEWRITING MACHINE

Miles H. Mann, West Hartford, Conn., assignor to
Underwood Elliott Fisher Company, New York,
N. Y., a corporation of Delaware

Application November 25, 1938, Serial No. 242,337

17 Claims.

(Cl. 197—66)

This invention relates to a typewriting machine and more particularly to devices whereby the typing carriage upon reaching a line-end position is automatically caused to be returned to a line-start position. Such a machine is generally exemplified in Patent No. 1,238,908 to F. A. Hart, dated September 4, 1917, and Patent No. 1,679,741 to H. L. Pitman, dated August 7, 1928.

In certain kinds of work, it is required to change frequently from a normal line-end position of the carriage to a different line-end position. The typing of telephone toll bills is an example of such work. The toll bill lists a subscriber's calls for a given period and the data for each call is typed on its individual line of the bill. The data for an ordinary call may consist of the place called and the toll charge. Thus, ordinary calls may be typed within uniform line lengths covering merely a place-called column and a toll-charge column of the bill. As the final character is typed for the entry in the last of these columns in a line for an ordinary call, the carriage takes a final step to what may be called the ordinary line-end position and the carriage thereby engages and actuates a carriage return starter or other suitable device to cause automatically the carriage to be returned to line-start position.

Other calls are notated with additional data such as a tax upon a toll charge exceeding a specified amount, and a code symbol. The bill form, therefore, includes, after the previously mentioned columns, a tax column and a code column.

It will be understood that preparatory to extending the typing of a call line on the bill into the tax and code columns, the automatic start of the return of the carriage from the ordinary line-end position must be prevented.

An object of the invention is to provide simple, efficient, time and labor saving means for preventing, in respect of typing extended lines, the automatic start of returning the carriage from the ordinary line-end position.

A further object is to provide means whereby, whenever there is such particular operation of the typing mechanism as occurs in or for typing a toll charge on the bill that exceeds a specified amount, that operation itself automatically determines that the carriage will not be caused to be returned automatically from the ordinary line-end position.

Further, such particular operation may also determine that the carriage will automatically be caused to be returned from an extended-line-end position.

Still further, concomitantly with the return movement of the carriage, it may be determined automatically that thereafter, that is, until such particular operation of the typing mechanism is again effected, the carriage will automatically

be caused to be returned from the ordinary line-end position.

Thus, one advantage afforded by the invention is that it relieves the typist of the necessity of observing or noting whether the amount or toll charge to be typed exceeds the specified amount and is therefore taxable. Correspondingly, the typist is relieved of the necessity of making adjustment for determining automatic initiation of the return of the carriage in respect of a normal line length or an extended line length.

Still another object of the invention is to have said means, namely, the means that respond to said particular or taxable toll charge typing operation, readily applicable to existing forms of typewriting machines.

The foregoing and other objects, features and advantages will be apparent from the following description of a preferred embodiment of the invention, illustrated in the accompanying drawings, in which:

Figure 1 represents a telephone toll bill.

Figure 2 is a cross sectional side view of a typewriter employing the invention.

Figures 3 and 4 are, respectively, front elevation and plan views of said typewriter.

Figure 5 is a perspective of the key controlled carriage controlled portions of the mechanism.

Figure 6 is a perspective showing a portion of the mechanism at the front of the carriage.

Figure 7 is a diagram illustrating operations of parts of the mechanism.

Figure 8 is a diagram illustrating a different operation of the Figure 7 parts.

Numeral type keys 10 and alphabet type keys 11 of the usual keyboard are mounted on key levers 12 connected by bell cranks 9 to type bars 13 fulcrumed at 14. By means of said keys, said type bars are swingable upwardly and rearwardly to print against a toll bill sheet 15 feedable around a platen 16. The platen is mounted in a carriage 17 that includes a frame having a front bar 18 having roller engagement at 19 with a front track 20, the carriage frame also having lugs 21 engaging a rear track 22. The tracks 20, 22 are supported by side frame-members 23 of the machine framework.

A spring motor 24, escapement mechanism 25, and a carriage feed rack 26 cooperate to feed said carriage 17, and its platen 16, in letter-feed direction at operations of the type bars 13 or the usual space key 21.

The front bar 18 of the carriage has a tappet 30 to engage and depress a cam lever 31 when the carriage, in its advance, reaches a predetermined line-end position, the depression of said cam lever in turn rocking a transverse bar 32 downwardly, said bar 32 having side arms 33 fulcrumed loosely upon a rock shaft 34 journaled in the frame side-members 23. A spring 28, Figure 4, normally upholds the bar 32 against a

stop 29. Said bar 32 has an ear 35 connected by a link 36 to a lever 37 turnable about a pivot stud 38 on the framework. Said lever 37 engages a stud 39 on a trip link 40 for lifting the latter out of latching connection with a key-lever comb plate 41. Said trip link 40 is pivotally connected at 43 to an arm 44 of a rock shaft 45 having suitable bearings, not shown, in the framework. Said rock shaft 45 is connected by arm 46, link 47, and arm 48 to a rock shaft 49 also suitably journaled in the framework, to clutch or unclutch said pinion with a clutch collar 53 on said shaft 52. Said shaft 52 has a reduction gear connection 54 to a shaft 55 extending from an electric motor 56 mounted upon the rear of the typewriter frame.

The rock shaft 45 has an arm 51 to which is pivoted a pusher 58 extending rearwardly to control a switch, not shown, for starting and stopping said motor.

When the carriage tappet 30, at a line-end position of the carriage, depresses the cam lever 31, the transverse bar 32 and link 36 are correspondingly depressed, thereby rocking the lever 37 counter-clockwise of Figure 2 to lift and release the trip link 40 from interlock with the comb plate 41. It results that a spring 60 moves said trip link rearwardly, thereby rocking the shaft 45 counter-clockwise and the shaft 49 clockwise of Figure 2 to shift the carriage return pinion 51 into clutch with the drive shaft collar 53. The counter-clockwise rotation of the shaft 45 also acts through the pusher 58 to cause the switch, not shown, to close to start the motor 56. The resulting rotation of the pinion 51 moves the carriage rightwardly or in return direction, as viewed from the front of the machine, said pinion meshing with a rack 61 on the carriage.

When the carriage in its power driven return movement reaches a predetermined point, the carriage tappet 30 encounters and depresses a dog 62 that is keyed to the rock shaft 34 thereby rocking said shaft 34 clockwise of Figure 2 to turn the shafts 45, 49 to shift the carriage return pinion 51 forwardly to unclutch it from the drive shaft collar 53. The carriage-tappet-rocked shaft 34 has a suitable operating connection, not shown, to the rock shaft 45. The rotation of the shaft 45 that results in unclutching the pinion 51 from the drive shaft collar 53 also restores the trip link 40 to latched position and also draws the pusher 58 forward to cause the switch, not shown, to open to stop the motor.

A carriage-return-limiting margin-stop body 71, Figure 4, has a stop lug 72 that cooperates with a counter-stop 73 on the front bar 18 of the carriage for finally arresting the carriage return movement after the carriage tappet 30 has served to depress the dog 62 to disconnect the carriage from the motor. Said body 71 is supported partly on the rock shaft 34, without binding the latter, and partly on a cross rod 74 supported by the frame side-members 23 and held endwise as by collars 75, Figure 4. Ordinarily, the margin stop 71, 72 along with the dog 62, is adjustable laterally to different stations and is located at any station by means of a pawl 76, and teeth 77 on said cross-rod 74.

The mechanisms thus far described operate substantially as set forth in the aforesaid Pitman Patent No. 1,679,741 and Hart Patent No. 1,238,-

908, to which reference may be had for other details.

A work web 79 affords a succession of telephone-toll-bill forms 15 of the kind seen at Figure 1. Each form includes a "Place-called" column, an "Amt." or toll-charge column, a "Tax" column and a "Code" column. The work web 79 may be located transversely of the carriage and platen and may be guided around the latter by means of a work web chute 80, Figure 2, of the kind described in Patent No. 1,160,459, to J. A. B. Smith, dated November 16, 1915.

The first three typed lines "a" on the toll bill, Figure 1, exemplify ordinary calls, that is, calls for which the toll amount is less than 50¢. For such ordinary calls, no entry is typed in the "Tax" or "Code" columns of the bill and hence the cam lever 31 may be placed so that as the carriage takes the letter-feed step following the typing of the last digit of the amount, the carriage tappet 30 depresses said cam lever and thereby, as hereinbefore explained, automatically initiates or causes a return of the carriage by means of the motor mechanism.

The return limiting margin stop 71, 72, along with the dog 62, may be placed to terminate said return so that the carriage is left or settles at the letter space position corresponding to the place where the first character is to be typed in the "Place-called" column of the bill. If desired, the margin stop 71, 72 and dog 62 may be fixed against lateral displacement from their determined position as by a collar 82 suitably secured to the shaft 34. The dog 62 and the rock shaft 34 may have a spline connection 84 so that the dog may rock said shaft 34 and yet be shiftable along the latter.

The toll amount for a call may be 50¢ or more and, in that case, a tax charge is imposed and is to be listed on the bill in the "Tax" column and a code symbol may also be listed in the "Code" column. The typing of the line on the bill for such call, therefore, extends into the tax and code columns of the bill as exemplified by the lines "b," Figure 1. Therefore, in typing an extended or tax and code including line "b," the automatic causing of a return of the carriage from the line-end position determined for the ordinary call line "a" must be prevented and for this purpose the following mechanism may be provided.

The cam lever 31 is pivoted upon a headed stud 86 in an arm or wall 87 extending leftwardly from a body block 88 supported by, but not binding the rock shaft 34. A U-shaped clip 89 is suitably and rigidly fastened, as by riveting 85, Figure 2, to the wall 87 and embraces the cross rod 74 to keep said block 88 from turning about said shaft 34.

A transverse bar 91 is fulcrumed at one end on a fixed stud 92 spaced to the left of the body block 88 and extends rightwardly beyond the latter to a pivotal connection 93 with a link 94 that extends downwardly to a pivotal connection 95 with an ear 96 on a lever 97. Said lever 97 may be fulcrumed at 90, like the type key levers 12, and extends forwardly through a guide slot 100 in the comb plate 41. A spring 99 tends to keep the lever 97 and hence the link 94 and bar 91 in normal positions wherein said lever 97 stops against the upper end of said slot 100. In the normal position of the bar 91, a shoulder 101 thereof engages the left end of a cleat 103 suitably fastened, as by rivets, not shown, to the underside of the block 88. The cleat 103 has an ear 104 to which is attached a spring 105 tensioned to urge

the unit comprising 31, 88, 89, 103 leftwardly, said unit therefore tending to shift leftwardly.

The fulcrum stud 92 for the shouldered bar 91 may be in a block 106 supported on but not binding the rock shaft 34. At its part 107, the block 106 may be supported by the cross rod 74 and may be fixed to the latter by set screws 108. The block 106 also presents an anchor 109 for the spring 105.

With the lever 97 and bar 91 in normal positions, Figures 3 and 6, the spring 105 keeps the block 88 in normal position with its cleat 103 against the shoulder 101 of the bar 91, and the latter prevents leftward shift of the block 88. Thus, the cam lever 31 is located laterally in a normal position, Figures 3 and 6, wherein it will be engageable and depressible by the carriage tappet 30 to depress the transverse bar 32 and so cause automatically a power return of the carriage to line start position when the carriage takes the letter fed step following the typing of the last digit in the "Amt." column of the bill 15.

If the amount is, say, fifty cents or more and therefore subject to a tax, the typing of a line is to be extended into the "Tax" and "Code" columns. In order that the line may be thus extended, automatic causing of the return of the carriage from the "Amt." column is to be prevented. This is accomplished by causing the lever 97 to be depressed as will be explained presently. The bar 91 is, of course, depressed about its fulcrum 92 by depression of the lever 97, and its shoulder 101 is thereby depressed below the cleat 103 of the block 88. It results immediately that the block 88, and its cam lever 31, are shifted leftwardly, along the rods 34, 31, by the force of the spring 105 and it will be obvious that the leftward shift may be stopped by a secondary shoulder 110 of the depressed bar 91.

In its leftwardly shifted position, the cam lever 31 is stationed for coacting with the carriage tappet 30 to cause automatically a return of the carriage at the time when the carriage takes the letter-feeding step following the typing of the last character in the "Code" column of the bill, said last character representing the end of the extended line. The downstroke of the key lever 97, and hence of the bar 91, may be suitably limited by a stop 111 on the comb plate 41.

Depression of the lever 97 about its fulcrum 90 and concomitant leftward shift of the cam lever 31 may be effected automatically through such operation of the typing mechanism as occurs in typing a toll charge of, say, 50¢ or more in the "Amt." column of the bill 15. The mechanism for accomplishing this will now be described.

Brackets 112 of the carriage 17 support a rack 113 in which a plate-like stop 114 is placed. A vertical reed or counter-stop 115 is guided for vertical movement in a fixture 117 attached to the framework. A bracket plate 118 of the framework supports a fulcrum rod 119 for a tabulating key lever 120. A spring 121 keeps the parts in normal positions in which the top of a slot 122 of the reed bears on a cross rod 123 of the fixture 117, and the top end of the reed is out of the path of the stop 114 on the carriage. Thus, depression of the tabulating key lever 120 causes the reed 115 to be lifted into the path of the carriage stop 114 and, concomitantly, the reed rocks a shaft 124 which, by means of a connection not shown, disengages the carriage feed rack 26 from the usual pinion of the escapement mechanism 25 to release the carriage 17 for resulting tabulating movement by the carriage spring motor 24.

The tabulating features thus briefly described are substantially like in Patent No. 1,858,447 to W. F. Helmond, dated May 17, 1932, which may be referred to for a fuller description.

5 The stop 114 may preferably be so placed, at one of the letter-spaced rack stations 111, relatively to the reed 115 that upon operation of the tabulating key lever 120, the carriage will be tabulated to the position for the tens-of-cents place or denomination in the "Amt." column of the bill. In Figure 1 the arrow represents the printing point and the tens-of-cents place in the "Amt." column at the printing point. Said tabulating key lever 120 may be operated after typing the last character in the "Place-called" column. If the "Amt." to be typed is above the tens-of-cents denomination, the usual back spacer 126, Figure 4, may be operated to bring the carriage back for typing in, say, the units-of-dollars or tens-of-dollars denomination in the "Amt." column.

When the carriage is positioned so that the tens-of-cents place of the "Amt." column is at the printing point, the top edge of the carriage stop 114, working as a tappet, will have engaged a cam edge 127 of a jack or lever 128 so that the latter will have been rocked, clockwise, to the Figure 7 position about a fulcrum stud 129 on an arm 130 of a plate 131 of the fixture 117.

25 Similarly, when the carriage is positioned so that the units-of-dollars place or the tens-of-dollars place of the "Amt." column is at the printing point, the tappet 114 will have also engaged a cam edge 132 of a jack or lever 133 so that the latter will have been rocked clockwise about the stud 129 to the Figure 8 position.

30 Each of the levers 128, 133 is bent forwardly as at 134 for connection, by a link 135, to a corresponding similarly bent intermediate lever 136 pivoted on a stud 137 passing through the fixture plate 131 into the fixture 117. Each intermediate lever 136 is articulated as at 138 to a corresponding one of upright thrust rods 139, 140. Said thrust rods each have a slot 141 for the cross rod 123 and the lower end of each thrust rod laterally fits a guide slot, as at 142, in the fixture 117. Each thrust rod is operatively connected at its lower end, as at 143, to a corresponding bell crank 144 fulcrumed on the rod 119.

35 The bell crank 144 corresponding to the cents denomination lever 128 is connected by a link 145 to a plate 146 extending crosswise only under the numeral key levers 12 of the values 5, 6, 7, 8 and 9. Similarly, the bell crank 144 corresponding to the dollars denomination lever 133 is connected by a link 147 to a plate 148 extending crosswise only under the numeral type key levers 12 of the values 1, 2, 3 and 4. Each link, 145, or 147, is pivotally connected to a rearwardly extending ear 149 of the corresponding plate 146 or 148, and each plate has a pair of forwardly extending ears 150 at which the plate is pivoted to corresponding arms 151 rigidly fastened to a transverse rock shaft 152 journaled in the framework. Another arm 153 rigidly fastened to said rock shaft has a lateral pin 154 for engaging the lever 97 that is depressible for causing a leftward shift of the cam lever 31 to prevent initiation at the "Amt." column of a return of the carriage.

40 Each train, from the lever 128 or the lever 133 to the corresponding plate 146 or 148, is held in normal position by a spring 155 connected between the bell crank 144 and an anchor bar 156.

of the fixture 111, and said normal position may be determined by the bottom of the thrust rod slot 141 abutting the cross rod 123.

In the normal positions of said trains, their respective plates 146, 148 stand, as represented by the full line position of the plates in Figure 2, clear of tongues 157 provided on the several numeral key levers 12.

It will be apparent, now, that if either or both levers 128, 133 stand rocked by means of the tappet 114 on the carriage, the corresponding plate or plates 146, 148 will stand rocked, counter-clockwise, to the dotted line position in Figure 2, under the numeral type key lever tongues 157.

Considering, now, that the carriage has been positioned for starting the typing of a toll charge at the tens-of-cents place in the "Amt." column, it will be seen that only the lever 128 will stand rocked and the corresponding plate 146 will stand placed under the tongues 157 of the numeral key levers 12 having the values 5, 6, 7, 8 and 9, as in Figure 7. In such position of the carriage, the lever 133 will not stand rocked because its cam edge 132 is proportioned so that the carriage tappet 114 has passed therefrom, and therefore the corresponding plate 148 will stand clear of the tongues of the key levers having the values 1, 2, 3 and 4. Thus, with the carriage positioned for the tens-of-cents place in the "Amt." column, operation of any one of the numeral key levers 10 for 5, 6, 7, 8 or 9 avails, through the effectively positioned plate 146, to rock the shaft 152 and thereby depress the lever 97 by means of the rock shaft arm 153 and its pin 154, and cause automatically a leftward shift of the cam lever 31 for preventing automatic initiation of a return of the carriage from the "Amt." column. Further, while said numeral key levers for the values 5, 6, 7, 8 and 9 are thus effective, the remaining key levers, for the values 1, 2, 3 and 4, 40 are not effective in this wise at the tens-of-cents place, since the corresponding plate 148 is not effectively positioned.

Consider, now, that the carriage is in position for starting the typing of a toll charge either at the units-of-dollars place or tens-of-dollars place in the "Amt." column. In that case, not only will the lever 128 stand rocked but the lever 133 will also stand rocked, by the tappet 114, and therefore both plates 146, 148 will stand rocked to effective positions under the tongues 157, as in Figure 8, to the end that, with the carriage positioned for typing at the dollars place in the "Amt." column, operation of any numeral key lever 12 from 1 to 9 in value, inclusive will result in automatic operation of the lever 97 for effecting a leftward shift of the cam lever 31.

In completing the typing of a toll charge by typing the character in the units-of-cents place of the "Amt." column, any one of all the numeral key levers 12 from 0 to 9 may be used. Therefore, the cam edges 127, 132 are proportioned so that as the carriage moves from the tens-of-cents place to the units-of-cents place, the tappet 114 leaves said cam edges and the springs 155 may operate to restore the trains, from the levers 128, 133 to the plates 146, 148, in order to remove said plates from under the tongues 157. Thus, in typing a toll charge less than 50¢, say, for example, a toll charge of 45¢, the operation of the key lever for typing the "5" in the units-of-cents place in the "Amt." column will not effect a leftward shift of the cam lever 31 as would be the case if that key lever were used to type "5" in the tens-of-cents place in the "Amt." column. 75

It will be understood that the rightward extent of the cam edges 127, 132 may be commensurate with the desired number of places in the "Amt." column preceding the tens-of-cents place. 5 Thus, Figures 7 and 8 may be considered as representing an extent commensurate with typing toll charges up to 99.99 and including a punctuation space between dollars and cents, and the tappet 114 may be considered as being capable of rocking either lever 128 or 133 only in the letter feed step which places the carriage in the tens-of-dollars place of the "Amt." column.

Referring now to the toll bill, Figure 1, the 15 typing of the toll charges in the "Amt." column is particularly illustrative for the operation of the mechanism described. Thus, with the carriage positioned at the tens-of-cents place for typing in the "Amt." column in each of the lines "a," only the plate 146 of the two interponents 20 or plates 146, 148 stands rocked to effective position as in Figure 7 and therefore only the key levers 12 for 5, 6, 7, 8 and 9 will be operatively connected to the lever 97, and the key levers 12 for 1, 2, 3 and 4 will not be so connected. It 25 follows that if the amount typed is less than 50, as exemplified by the amounts "40", "30", and "10", in the first three lines "a" of the bill, the lever 97 will not be operated through the typing of these amounts and therefore the cam lever 31 will remain positioned, by means of the latch bar shoulder 101, so as to be engaged by the carriage tappet 30 as the carriage takes a letter-feed step following the typing of the last digit 30 of the amount. The carriage is in such case 35 automatically caused to be returned immediately upon typing the amount in each of the lines "a" of the bill.

In the fourth line of the Figure 1 bill, the amount is "50" and since the numeral agent or key lever 12 for typing 5 in the tens-of-cents place is one of those operatively connected to the lever 97 by means of the carriage controlled train 128—146, the operation of that numeral key lever concomitantly operates said lever 97 to depress the latch bar 91 and thus cause the cam lever 31, with its supporting block 88, to be shifted leftwardly by the spring 105 preparatory to extending the typing of said fourth line of the bill into the "Tax" and "Code" columns. The 45 leftward shift of the block 88, with the cam lever 31, is arrested by the secondary shoulder 110 of the latch bar 91 so as to place said cam lever 31 for engagement by the carriage tappet 30 as the carriage takes a letter-feed step following the 50 typing of the entry in the "Code" column, the carriage being thus automatically caused to be returned from said "Code" column. 55

In the fifth and sixth lines "b" of the Figure 1 bill, the toll charges typed in the "Amt." column are respectively 1.50 and 14.30. With the carriage positioned for the units-of-dollars or the tens-of-dollars place in the "Amt." column, both plates or interponents 146, 148 will stand rocked under the numeral key lever tongues 157, as in Figure 8, so that all of the numeral agents or key levers 12 from 1 to 9 will be operatively connected to the lever 97. It follows that the typing of any digit from 1 to 9 in the dollars places in the "Amt." column will automatically cause said lever 97 to be operated for causing the cam lever 31 to be shifted leftwardly, preparatory to extending the typing into the "Tax" and "Code" columns and having the carriage automatically returned upon typing the entry in the "Code" column. 65 70 75

The rightward or return movement of the carriage may serve automatically to restore or shift the unit 31, 88, 89, 103 back to normal position. For this purpose, the clip 89 includes a lateral extension 159 to which is secured, by a screw and slot adjustment device 160, a plate 161 engageable by a pin 162 in the front bar 18 of the carriage. By means of the adjustment device 160, the plate 161 may be set so that said unit will have been restored or shifted rightwardly by the pin 162, in the carriage return movement, to place the left end of the cleat 103 about $\frac{1}{2}$ of an inch to the right of the latch bar shoulder 101 when the carriage counterstop 73 stops against the stop lug 72. This permits the latch bar 91 to rise under the force of the key lever spring 99 and its shoulder 101 to confront the left end of the cleat 103 again. It will be obvious that when said unit is in its leftwardly shifted position, the bottom of the cleat 103 may abut 20 a step 158 of the latch bar 91 to maintain the latter in depressed position.

It will be understood that after banking or stopping in its return movement against the stop lug 72 the carriage may have the usual drop back 25 movement of about a letter space due to the usual back lash of the escapement 25. At the end of such drop back movement, the carriage will be settled at the letter space or line start position corresponding to the first character space in the "Place-called" column. By such drop back movement of the carriage, its pin 162 recedes from the plate 161 to permit the unit 31-103 to be released from the bar shoulder 101 by depression of the lever 97.

The wall 87 of the unit 31-103 may have a lug 163 to coat with the tappet 30 for positively limiting leftward movement of the carriage at either position of said unit. The dog 62 may have an anti-friction roller 164 for engagement with said tappet 30. The cam lever 31 may have a nose 165 for engaging the bar 32 and said cam lever may be stopped against upward displacement by a pin 166 in the wall 87. The bar 32 may be similar to the usual toothed bar employed in Underwood machines.

The lever 97 may be provided with a key 167 so that it may be manually operable independently at will if desired, said lever 97 being independently operable by reason of the one-way pin connection at 154 with the mechanism through which the numeral agents or key levers 12 operate said lever 97.

The machine may be provided with a palm key tabulating lever 169 pivoted at 170 to the machine frame and connected by an intermediate lever 171, pivoted at 172 to the machine frame, to one end of a bail 173 loosely fulcrumed on the rock shaft 152. The opposite end of said bail 173 is connected by a link 174 to the tabulating key lever 120.

Variations may be resorted to within the scope of the invention, and portions of the improvements may be used without others.

What is claimed is:

1. In a typing machine having numeral type agents and a carriage for typing a line, including an amount column, on a work sheet form; carriage-return mechanism, a carriage-operable controller therefor normally operative after typing in said amount column for automatically causing said carriage to be returned by said mechanism, a device operable preparatory to extending the typing of the line beyond the amount

5 column, means causing said controller to become conditioned relatively to said carriage in response to operation of said device for preventing automatic return of the carriage from the amount column, a normally ineffective operative connection from certain of said numeral type agents to said device, and means operable by said carriage at said column to render said connection effective whereby said device is operated automatically when an amount is typed in said column by said certain type agents.

2. In a typing machine having numeral type agents and a carriage for typing a line, including an amount column, on a work sheet form; carriage-return mechanism, a carriage-operable controller therefor normally operative after typing in said amount column for automatically causing said carriage to be returned by said mechanism, a device operable preparatory to extending the typing of the line beyond the amount column, means causing said controller to become conditioned relatively to said carriage in response to operation of said device so that said controller will be operative for automatically causing said carriage to be returned from a certain place beyond the amount column instead of from the amount column, a normally ineffective operative connection from certain of said numeral type agents to said device, and means operative by said carriage at said column to render said connection effective whereby said device is operated automatically when an amount is typed in said column by said certain type agents.

3. In a typing machine having type agents and a letter feeding carriage cooperative therewith; motor mechanism for returning said carriage, an element on said carriage, another element encounterable by said carriage element for controlling said motor mechanism to return said carriage at a line end, an operable device, means causing said elements to become relatively shifted from a normal-line-end-determining position to an extended-line-end-determining position in response to operation of said device, and normally ineffective means operatively connected to and rendered effective by the carriage at a certain carriage position before the normal-line end, to operatively connect said device to certain of said type agents, whereby the operation of said certain of said type agents concomitantly operates said device to cause said shift of said elements.

4. In a typing machine having type agents and a letter feeding carriage cooperative therewith; motor mechanism for returning said carriage, an element on said carriage, another element encounterable by said carriage element to cause said motor mechanism to return said carriage at a line end, an operable device, means causing said elements to become relatively shifted from a normal-line-end-determining position to an extended-line-end-determining position in response to operation of said device, normally ineffective means operatively connected to and rendered effective by the carriage at a certain carriage position before the normal-line end, to operatively connect said device to certain of said type agents, whereby the operation of said certain of said type agents concomitantly operates said device to cause said shift of said elements, and means acting concomitantly with return movement of the carriage to relatively shift said elements back to the normal line-end-determining position.

5. In a typing machine having type agents and a letter feeding carriage; carriage-return mechanism, a carriage-operable controller therefore, normally effective at a line end position of the carriage to automatically cause said carriage to be returned by said mechanism, an operable device, means causing said controller to become conditioned relatively to said carriage in response to operation of said device for preventing the automatic return of said carriage from said line end position, a normally ineffective connection conditionable to operatively connect said device to certain of said type agents, and means enabling the carriage at a certain position of the latter before the line end to so condition said connection whereby the operation of said certain of said type agents may concomitantly operate said operable device.

6. In a machine of the character described, the combination with selectively operable numeral agents and a step-by-step shiftable carriage cooperative therewith for producing an amount numeral-by-numeral, of a device which is to be operated only if the amount produced is within a predetermined range of numerical values determined by which agents are accordingly operated and by consonant denominational positioning of the carriage in an amount column zone, and normally ineffective means operatively connected to and rendered effective by means of the carriage in accordance with certain denominational positioning thereof in the column zone to enable such agents as may be operated to produce any amount within said range to effect operation of said device, in contradistinction to avoiding effecting operation of said device when the amount produced in the zone is not within said range.

7. In a typing machine having a set of numeral type actions from 1 to 9, and a letter feeding carriage cooperative therewith; a carriage return mechanism, a shiftable member for controlling said mechanism and normally positioned relatively to the carriage so as to be engageable by the carriage to cause said mechanism to return said carriage from a normal line-end position, an operable device, means causing said member to become shifted to an extended-line-end-determining position in response to operation of said device, an interponent placeable to operatively connect a certain part of said set of numeral type actions to said device, another interponent placeable to operatively connect another part of said set of type actions to said device, and means enabling the carriage at different predetermined positions thereof before the normal-line-end position to select and place said interponents to connect said device and numeral type actions according to a predetermined plan, whereby coincidentally with the operation of said type actions for typing certain amounts before the normal line end said device becomes operated automatically.

8. In a typing machine having a set of numeral type actions from 1 to 9, a letter feeding carriage cooperative therewith, and a carriage return mechanism; a shiftable member normally positioned, relatively to the carriage, and cooperative with the carriage to automatically cause said mechanism to return the carriage from a predetermined column zone including a plurality of denominations, an operable device, means causing said member to become shifted in response to operation of said device for determining return of the carriage from a predetermined position beyond said zone, an interponent place-

able to operatively connect a certain part of said set of numeral type actions to said device, and means enabling the carriage at a particular denomination of said zone to so place said interponent.

9. In a typing machine having a set of numeral type actions from 1 to 9, a letter feeding carriage cooperative therewith, and a carriage return mechanism; a shiftable member normally positioned, relatively to the carriage, and cooperative with the carriage to automatically cause said mechanism to return the carriage from a predetermined column zone including a plurality of denominations, an operable device, means causing said member to become shifted in response to operation of said device for determining return of the carriage from a predetermined position beyond said zone, an interponent placeable to operatively connect a certain part of said set of numeral type actions to said device, another interponent placeable to operatively connect another part of said set of numeral type actions to said device, and means enabling the carriage at different denominations of said zone to place said interponents selectively.

10. In a typing machine having amount typing instrumentalities and a carriage advanceable from a line starting position to an amount column zone and, thence, beyond said zone; carriage return mechanism, adjustable means cooperative with said carriage and normally adjusted for automatically causing said mechanism to return said carriage immediately after the operation of said typing instrumentalities for typing an amount in said zone, and means acting automatically at said zone, if the amount typed by said instrumentalities is of a predetermined value, to adjust said adjustable means to prevent the automatic return of the carriage from said zone, said means including a normally ineffective operative connection from said typing instrumentalities to said adjustable means and also including means operable by the carriage at said zone to render said operative connection effective.

11. In a typing machine having numeral type actions, a letter feeding carriage cooperative therewith, and a motor mechanism for returning said carriage; an element on said carriage, another element encounterable by said carriage element to cause said motor mechanism to return said carriage, means tending to relatively shift said elements from a normal line-end determining position to an extended line-end determining position, a latch device normally holding said elements in their relative normal line-end determining position, and means operative under control of the carriage at a predetermined position of the carriage before its normal line-end position for operatively connecting said latch device to certain ones of said numeral type actions, whereby the typing of an amount involving operation of any one of said certain type actions at said predetermined carriage position automatically trips said latch device to permit a relative shift of said elements to the extended line-end determining position.

12. In a typing machine having numeral type agents and a carriage for typing a line, including an amount column, on a work sheet form; carriage return mechanism, a carriage-operable controller therefore normally operative after typing the amount in said column for automatically causing said carriage to be returned by said mechanism, a device operable preparatory to extending the typing of the line beyond the amount

column, means causing said controller to become shifted relatively to said carriage in response to operation of said device for preventing automatic return of the carriage from said column, normally ineffective connecting means conditionable to operatively connect certain of said type agents to said device, tappet means movable with the carriage, and means operable by said tappet means at said column to condition and thereby render effective said connecting means.

13. In a typing machine having numeral type agents and a carriage for typing a line, including an amount column, on a work sheet form; carriage return mechanism, a carriage-operable controller therefor normally operative after typing the amount in said column for automatically causing said carriage to be returned by said mechanism, a device operable preparatory to extending the typing of the line beyond the amount column, means causing said controller to become conditioned relatively to said carriage in response to operation of said device for preventing automatic return of the carriage from said column, normally ineffective connecting means conditionable to operatively connect certain of said type agents to said device, tappet means movable with the carriage, and means operable by said tappet means at said column to condition and thereby render effective said connecting means, said tappet means and the last-named means being relatively adjustable to accord with a variably predetermined zone of carriage travel for the amount column.

14. In a typing machine having a set of numeral type agents and a letter feeding carriage cooperative therewith for typing a line, including an amount column, on a work sheet form; a carriage return mechanism, a carriage-operable controller therefor normally operative after typing the amount in said column for automatically causing said carriage to be returned by said mechanism, a device operable preparatory to extending the typing of the line beyond the amount column, means causing said controller to become conditioned relatively to said carriage in response to operation of said device for preventing automatic return of the carriage from said column, a plurality of normally ineffective connections corresponding to different predetermined selections of said type agents, said connections being conditionable to operatively connect said device to said selected type agents, a plurality of jacks corresponding to and operatively connected to said connections, and tappet means movable with the carriage to selectively operate said jacks and thereby condition the corresponding connections when the carriage is at different denominational places in the amount column zone, whereby the typing of amounts of certain values involving operation of any one of said selected type agents before the normal line-end, operates said device automatically.

15. In a typing machine having a set of numeral type agents, and a letter feeding carriage cooperative therewith for typing a line, including an amount column, on a work sheet form; a carriage return mechanism, a carriage-operable controller therefor normally operative after typing the amount in said column for automatically causing said carriage to be returned by said mechanism, a device operable preparatory to

extending the typing of the line beyond the amount column, means causing said controller to become conditioned relatively to said carriage in response to operation of said device for preventing automatic return of the carriage from said column, a plurality of normally ineffective connections corresponding to different predetermined selections of said type agents, said connections being conditionable to operatively connect said device to said selected type agents, a plurality of jacks corresponding to and operatively connected to said connections, and tappet means movable with the carriage to selectively operate said jacks and thereby condition the corresponding connections when the carriage is at the amount column zone, whereby the typing of amounts of certain values involving operation of any one of said selected type agents before the normal line-end, operates said device automatically, said jacks and tappet means being arranged so that first one jack is actuated for one denominational position of the carriage in said amount column zone and so that both jacks are operated when the carriage is at another denominational position in said zone.

16. In a typing machine having numeral type agents and a carriage for typing a line including an amount column on a work sheet form; carriage-return mechanism, a carriage-operable controller therefor normally operative after typing in said amount column for automatically causing said carriage to be returned by said mechanism, an operable device, means causing said controller to become conditioned relatively to said carriage in response to operation of said device for preventing automatic return of the carriage from the amount column, a normally ineffective operative connection from certain of said type agents to said device, means operable by said carriage at said column to render said connection effective whereby said device is operated automatically when an amount is typed in said column by said certain type agents, and a key operatively connected to said device and manually operable at will for operating said device independently of said type agents and carriage.

17. In a typing machine having numeral type agents and a carriage for typing a line including an amount column on a work sheet form; carriage-return mechanism, a carriage-operable controller therefor normally operative after typing in said amount column for automatically causing said carriage to be returned by said mechanism, an operable device, means causing said controller to become conditioned relatively to said carriage in response to operation of said device for preventing automatic return of the carriage from the amount column, a normally ineffective operative connection from certain of said type agents to said device, means operable by said carriage at said column to render said connection effective whereby said device is operated automatically when an amount is typed in said column by said certain type agents, a key operatively connected to said device and manually operable at will for operating said device independently of said type agents and carriage and means automatically actuated by the return movement of the carriage to restore said controller.

MILES H. MANN.
